PERFORATING DEVICE

William H. Bedinghaus, Cincinnati, Ohio

Application July 16, 1956, Serial No. 598,015

2 Claims. (Cl. 23—65)

This invention relates to a device for forming a plurality of rows of perforations or the like in a strip or web of paper or the like.

An object of this invention is to provide a device which makes a plurality of closely spaced parallel rows of perforations or lines of weakening in a web.

A further object of this invention is to provide a device of this type in which a plurality of independently swinging spring-pressed perforator wheels co-operate to steady each other against sidewise movement while each wheel is free to move toward or away from the web under the urging of its spring sufficiently for proper adjustment of the pressure on each wheel.

A further object of this invention is to provide a device of this type in which the pressure on each perforator wheel can be adjusted without disturbing adjustment of other wheels.

The above and other objects and features of this invention will be apparent to those of ordinary skill in the art to which this invention pertains, from the following detailed description and the drawings, in which:

Figure 1 is a view in end elevation of a device constructed in accordance with an embodiment of this invention, the device being shown mounted on a printing press, only a fragmentary portion of the printing press being shown, the printing press being shown partly in elevation and partly in section.

Figure 2 is a view partly in side elevation and partly in section of the perforating device;

Fig. 3 is a view in section taken on the line III—III in Fig. 2;

Fig. 4 is a view in section taken on the line IV—IV in Fig. 3; and

Fig. 5 is a view in side elevation of one of the swinging plates of the device and the perforator wheel associated therewith.

In the following detailed description, and the drawings, like reference characters indicate like parts.

In Fig. 1, a perforating device constructed in accordance with an embodiment of this invention is indicated generally at 10. The device is mounted on a rod 12. The rod 12, in turn, is mounted on a framework 13 of a printing press, only a portion of which is shown. A web of paper 14 travels along the printing press from printing rolls (not shown), under a guide roll 16, and over a back-up roll 17 to a windup roll 18. The back-up roll is parallel to and closely spaced from the rod 12 on which the perforating device 10 is mounted. A plurality of perforator wheels 19, which form a portion of the perforating device, grip the web as it passes over the back-up roll 17 to co-operate with the back-up roll and perforate the paper of the web. As shown in Fig. 3, the edge of each perforator wheel may be provided with serrations 20 of appropriate dimensions for forming the desired perforations.

The perforating device includes end plates 21 and 22 (Fig. 2) which are heavy, rigid plates. Each end plate is slotted as indicated at 23 in Fig. 3, to provide spaced,

2

parallel guide flanges 24 and 26. A slide member 27 of generally H-shape in section, as shown in Fig. 4, rides between the guide flanges on each end plate (see Fig. 3). Each slide member 27 is provided with a bore 29 having a counterbored lower section 30 (see Fig. 2). Each H-shaped member 27 is linked to the end plate in which it is mounted by a screw 31. Each screw 31 is mounted in and threaded to a bore 32 in the upper portion of one of the end plates. The lower end of each screw carries a lug 33 having a shank which is received in the bore 29 and an enlarged lower end 34 which is received in the counterbore 30. As the screws 31 are turned, the end plates are moved up and down with respect to the rod 12. As shown, each of the end plates is substantially perpendicular to the rod 12 and to the back-up roll 17. Each of the slide members is also provided with a threaded lower bore 34a. Thumb screws 34b mounted in the bores 34a engage the rod 12 to lock the slide members in place thereon.

20 The end plates 21 and 22 are bridged by rigid bars 35 and 36 which are attached to the end plates by screws 37. In addition, pivot rods 38 and 39 and stop rods 41 and 42 span the end plates and are parallel to the back-up roll 17 and the support rod 12. Each of the pivot rods serves as a support for a plurality of swinging plates 43. Details of construction of one of the swinging plates 43 are shown in Figs. 3 and 5. The plate 43 is of inverted, L-shape and includes a main arm 44 and a side arm 46. A bore 47 in the side arm receives the pivot rod 38. The arms of the plate have flat, parallel side faces 48 and 49. As shown in Fig. 2, each of the side faces of each swinging plate engages flatwise against a face of an adjacent swinging plate or of one of the end plates, so that the plates co-operate to maintain their parallelism.

35 As shown in Fig. 5, the lower end of the main arm of each swinging plate 43 is cut away or slotted as indicated at 50, to form the shoulder 51 and a lower leg portion 52 of reduced thickness. One of the perforator wheels 19 is mounted in the slot 50. The wheel 19 is mounted on a stub shaft 53 which is mounted in the swinging plate and extends parallel to the pivot rods. A bearing 54 (Fig. 3) for the wheel 19 is pressed on the stub shaft.

The wheel 19 has two flat annular faces 56 and 57 on opposite sides thereof. The face 56 engages flatwise against a flat inner face 58 of lower leg portion 52. The face 57 engages a flat, outer face 59 of the adjacent swinging plate, as shown in Fig. 2. Thus, both faces of each wheel are steadied. As shown in Figs. 2 and 5, the edge of each perforator wheel is sharpened on a bevel 60 which intersects a flat face 61 on the wheel. The face 61 is parallel to faces 56 and 57 so that, when the wheel is sharpened, the spacing between the plane of the cutting edge and the faces 56 and 57 remains constant. Each of the swinging plates is pressed downwardly by a spring 62, as shown most clearly in Fig. 3. Each spring is mounted in a bore 63 in one of the rigid bores 35 and 36. An adjustment screw 64 mounted in the bore adjusts the pressure of the spring. As shown in Fig. 3, the stop bars 41 and 42 limit the extent to which the swinging plates can swing. The spring-receiving bores are directed toward the back-up roll and each of the swinging plates has a shoulder portion 66 opposed to one of the bores which the spring of said one of the bores engages.

65 The perforating device is mounted on the rod 12 with the edges of the perforator wheels gripping the web against the back-up roll 17. Each of the swinging plates is adjusted individually by turning the screw associated therewith to provide appropriate compression in the spring thereof. Each of the swinging plates can swing in a plane perpendicular to the back-up roll but can not be cocked out of alignment. Each perforator wheel is supported on two opposite faces to prevent cocking thereof

and to maintain proper alignment. As shown most clearly in Figs. 1 and 3, the perforator wheels and the supports therefor are arranged in two rows on opposite sides of the rod 12 so that any tendency of the perforating device to swing about the rod 12 is balanced. Each of the perforator wheels grips the web against the back-up roll, as shown in Fig. 1.

The device is shown with serrated perforator wheels mounted thereon, but other types of wheels for producing other types of lines of weakening, such as score lines, or the like, may be used instead of the serrated edged wheels shown.

The perforating device described above and illustrated in the drawings, is subject to structural modification without departing from the spirit and scope of the appended claims.

Having described my invention, what I claim as new and desire to secure by Letters Patent, is:

1. A device for forming a plurality of lines of weakening in a web which comprises a back-up roll, a perforator support rod adjacent, spaced from, and substantially parallel to the back-up roll, a pair of slide members mounted on said perforator support rod, an end plate mounted on each slide member for sliding toward and away from the back-up roll, means for holding each end plate in selected position, rigid bar members linking the end plates to hold the end plates substantially perpendicular to the back-up roll, a pair of spaced pivot rods spanning the end plates and substantially parallel to the back-up roll, a plurality of flat swinging plates pivotally mounted on each of the pivot rods between the end plates, faces of each swinging plate engaging flatwise against faces of adjacent plates, a stub shaft mounted in each swinging plate spaced from the pivot thereof and substantially parallel to the pivot rods, a perforator wheel rotatably mounted on each stub shaft, each of said bar members having a plurality of bores directed substantially toward the back-up roll, there being a bore for each swinging plate, a compression spring mounted in each of the said bores, each of said swinging plates having a shoulder opposed to one of the bores, and spring back-up means in each of said bores, the spring means urging the swinging plates to pivot in a direction to bring the perforator wheels into co-operative relation with the back-up roll, the perforator wheels being arranged in two groups gripping the web against the back-up roll on op-

posite sides of a plane through the back-up roll and the perforator support rod.

2. A device for forming a plurality of lines of weakening in a web which comprises a back-up roll, a perforator support rod adjacent, spaced from, and substantially parallel to the back-up roll, a pair of slide members mounted on said perforator support rod, an end plate mounted on each slide member for sliding toward and away from the back-up roll, means for holding each end plate in selected position, rigid bar members linking the end plates to hold the end plates substantially perpendicular to the back-up roll, a pair of spaced pivot rods spanning the end plates and substantially parallel to the back-up roll, a plurality of flat swinging plates pivotally mounted on each of the pivot rods and between the end plates, faces of each swinging plate engaging flatwise against faces of adjacent plates, there being a slot in the end portion of each swinging plate remote from the pivot thereof having an inner wall parallel to the faces of the swinging plate, a stub shaft mounted in said end portion substantially parallel to the pivot rods, a perforator wheel rotatably mounted on each stub shaft, each perforator wheel having two oppositely facing flat annular bearing faces surrounding the stub shaft, one of said bearing faces being in flatwise engagement with the adjacent plate, the other of the bearing faces being in flatwise engagement with the inner wall of the slot of the swinging plate associated therewith, each of said bar members having a plurality of bores directed substantially toward the back-up roll, there being a bore for each swinging plate, a compression spring mounted in each of the said bores, each of said swinging plates having a shoulder opposed to one of the bores, and spring back-up means in each of said bores, the spring means urging the swinging plates to pivot in a direction to bring the perforator wheels into co-operative relation with the back-up roll.
